UNITED STATES PATENT OFFICE.

JOHN JANUCHOWSKY AND HEINRICH ALBERT, OF ST. LOUIS, MISSOURI.

BOTTLE-CAPPING MACHINE.

1,193,463.

Specification of Letters Patent.

Patented Aug. 1, 1916.

Application filed April 24, 1915. Serial No. 23,564.

To all whom it may concern:

Be it known that we, JOHN JANUCHOWSKY and HEINRICH ALBERT, citizens of the United States of America, and residents of the city of St. Louis and State of Missouri, have invented certain new and useful Improvements in Bottle-Capping Machines, of which the following is a specification.

The primary object of this invention is to provide an improved bottle capping machine that is adapted to apply caps or seals to bottles of varying sizes.

Another object is to provide an improved pressing, or squeezing, mechanism to a bottle capping machine in which the pressing members will automatically adjust themselves so as to firmly engage the caps to bottles which have varying diameters of necks.

A further object is to provide improved means for insuring the mounting of a cap on a bottle neck prior to the pressing or sealing operation.

Other and further objects will appear in the specification, and be specifically pointed out in the appended claims, reference being had to the accompanying drawings exemplifying the invention, and in which,

Figure 1 is a sectional view, showing this improved device attached to one end of a spindle, the parts thereof being shown in inoperative position. Fig. 2 is a sectional view, similar to Fig. 1, but showing the parts of the device in an operative position. Fig. 3 is a horizontal section taken on the line III—III, Fig. 1. Fig. 4 is an enlarged perspective of one of the adjustable cap pressing members. Fig. 5 is a vertical section taken on the line V—V, Fig. 1.

Referring to the drawings: 1 designates the lower end of a spindle, which is threaded at 2, and adapted to support a bottle capping head 3. Formed in the under side of said head is a chamber 4. The upper end wall 5 of said chamber has a concentric opening 6 formed therein. The side wall 7 of this chamber 4 is tapered and of a cone-shape, the upper end of said chamber being much less in diameter than its lower end.

Extending inwardly from the side wall 7, at the lower end of the chamber 4, is an

annular shoulder 8, said shoulder forming a cap receiving throat 9. Formed in the side wall 7 of the chamber 4 is a series of radially arranged vertical slots 10. Radially arranged against the inner surface 11 of the wall 7 are a series of cap pressing members 12, each of said members having a guiding portion 13 formed thereon. Each guiding portion of each member is engaged in one of the slots 10. A cap screw 14 is carried by each of said guiding portions 13, said cap screws adapted to have their heads bear against the outer surface 15 of the wall 7.

Mounted in the opening 6 of the end wall 5 is a plunger 16. Formed on the upper end of said plunger is a spring seat 17, which is adapted to receive a pressure spring 18. Formed on the plunger 16, and located in the chamber 4, is an annular shoulder 19. The under side of said shoulder is adapted to bear against the upper side of the horizontal portion 20 of each cap pressing member 12. This plunger 16 is preferably constructed in sections, there being an upper section 21, and a lower section 22, said sections being secured together by the centrally arranged screw 23. Formed in the lower section 22 is a shoulder 24. Said shoulders 19 and 24 of said plunger 16 form a reduced neck portion 25. The space provided by this neck portion between the shoulders 19 and 24 is adapted to receive the horizontal portions 20 of the cap pressing members 12. Each of the cap pressing members 12 has a depending portion 26. Each of said portions 26 of said pressing members has a cap receiving face 27.

Horizontally and radially arranged in the annular shoulder 8 are a plurality of spring-pressed plungers 28, said plungers being reciprocably mounted in the chambers 29. Each of said chambers is closed at one end by a screw 30.

In the operation of this improved bottle capping mechanism, when the pressing members 12 are inactive, the depending portions 26 thereof will rest on the shoulder 8 (see Fig. 1). In this construction, the embodiment shown relates to the capping or

sealing of milk bottles. When it is desired to seal a bottle, a cap 31 is engaged in the throat 9. The depending flange 32 of said cap will be engaged by the plungers 28, 5 thereby holding said cap in elevated position ready for engagement with the beaded mouth 33 of a bottle 34, which is mounted on a vertical reciprocating platform 35. When the platform 35 is elevated by a mechanism not shown, the bottle being carried by said platform will have its mouth engage against the under side of the cap 31. The elevating mechanism may, for instance, consist of a foot treadle or any other reciprocating mechanism, operating directly or 10 through the intermediary of a yielding means, to raise the platform 35, and the slight variation in the travel of the platform, required for different sizes of bottles, 15 may obviously be regulated in this manner. Such commonly known mechanisms are shown and described, for instance, in U. S. Patents Nos. 985,141 and 949,678. As the elevating of the bottle is continued, the cap 20 31 will be disengaged from the plungers 28, and will be carried upwardly until the top of said cap engages against the under side of the lower section 22 of the plunger 16. If, in the meantime, the cap has not been 25 come fully seated on the mouth portion 33 of the bottle, the action of the spring 18 upon the plunger 16 against the cap, and the upward movement of the bottle will cause said cap to be seated in proper position on the bottle, and the top edge of the bottle mouth will firmly engage the under side of the top of the cap. As the upward movement of the bottle is continued, the plunger 16 will be elevated against the pressure 30 of the spring 18, and the upper surface of the shoulder 24 will engage against the under side of the horizontal portions 20 of the cap pressing members 12, thereby carrying said members upwardly. As said cap 35 pressing members are being elevated, said members will be carried inwardly on account of their engagement with the tapering inner surface 11 of the side walls 7 of the chamber 4. As the members 12 are moved 40 inwardly, the cap engaging faces 27 of said members will eventually engage the depending flange 32 of said cap, and will firmly press said depending flange against the outside wall of the bead of the bottle neck (see 45 Fig. 2). After this has been done, it is seen that said members 12 cannot be moved any farther inwardly and upwardly. After the cap has been secured to the bottle, as just described, the platform 35 is lowered, there- 50 by removing the resistance of the bottle against the cap pressing members 12, and said members will return to their original positions in the slots 10, by their own weight, or by the pressure of the spring 18 against

the plunger 16. This downward movement 65 of said members will cause them to ride away from the cap which has just been secured to the bottle.

From an inspection of Fig. 2, it is to be seen that the cap pressing members 12 have 70 reached the limit of travel of their upward movement, the supposition being that the bottle shown in said view is of the smallest caliber. If a bottle having a larger diameter across the beaded neck than that shown were operated on by said members 12, said members would not travel as far upwardly as the position shown, because the faces 75 27 of said members would engage the depending flange of the cap against the outside of the bottle neck before said members reached their limited traveling position. This arrangement of slidingly mounted cap pressing members 12, which are adapted to travel inwardly as they travel 80 upwardly, provides means of securing the caps to bottles of varying sizes, as it is well known how bottles, which are supposed to be of a standard size, are liable to vary in size during the course of their manufacture. 85

What we claim is:

1. In a bottle capping machine, a head rigidly held against vertical movement, a series of radially arranged cap-pressing members slidably mounted in said head, inclined guideways for said members and co-acting means on said members and said guideways for retracting the members. 95

2. In a bottle capping machine, a head rigidly held against vertical movement, a series of radially arranged cap-pressing members slidably mounted in said head and a single means located in said head for guiding said members inwardly and upwardly, and retracting them outwardly. 100

3. In a bottle capping machine, a head rigidly held against vertical movement, a series of radially arranged cap-pressing members slidably mounted in said head and a single means located in said head for guiding said members inwardly and upwardly while said members are being elevated, and retracting them outwardly when the members are being depressed. 110

4. In a bottle capping machine, a head rigidly held against vertical movement, a series of radially arranged cap-pressing members slidably mounted in said head and a single means located in said head for guiding said members inwardly and upwardly while said members are being elevated, and a spring-cap plunger having one end extending beneath the upper portions 120 of said members and engaging therewith. 115

5. In a bottle capping machine, a head rigidly held against vertical movement, said heads having a cone-shaped wall with longi-

tudinal slots, an inwardly pointing cap-
pressing member slidably engaged in each
slot, said member being provided with re-
tracting means engaging the outside of said
wall and a spring-actuated plunger mounted
axially in the head, said plunger having
constant engagement with said member.

In testimony whereof, we have hereunto
set our hands, this 3d day of January, 1915.

JOHN JANUCHOWSKY.

HEINRICH ALBERT.

In the presence of—

H. G. FLETCHER,

CHARLES BILHARTZ.
